UNITED STATES PATENT OFFICE.

WALTER N. DERBY, OF ETNA, NEW HAMPSHIRE.

EXTENSION-LADDER.

SPECIFICATION forming part of Letters Patent No. 678,549, dated July 16, 1901.

Application filed April 17, 1901. Serial No. 56,386. (No model.)

To all whom it may concern.

Be it known that I, WALTER N. DERBY, a citizen of the United States of America, and a resident of Etna, county of Grafton, State 5 of New Hampshire, have invented certain new and useful Improvements in Extension-Ladders, of which the following is a specification.

My invention relates to an improvement in extension-ladders, and has for its object to 10 provide a ladder which can be raised and lowered and held at different altitudes, which is very simple, inexpensive, and durable in construction and easy to operate, and is an improvement on my Patent No. 326,205, dated 15 September 15, 1885.

My invention consists in the features and combination of features, as hereinafter more fully described and claimed.

In the drawings, Figure 1 is a front view 20 in elevation; Fig. 2, a central vertical section; Fig. 3, a detail view of the locking-lever; Fig. 4, a detail view of the tripping-dog; Fig. 5, a section, on an enlarged scale, of a portion of the two sections of the ladder, showing the 25 locking-lever and tripping-dog; Fig. 6, a sectional view showing the bearing-plates of the locking-lever and tripping-dog; and Figs. 7 and 8, top plan and sectional views, respectively, of the bearing-plate of the locking- 30 lever.

Referring to the drawings, in which like letters of reference denote like parts throughout the several views, A represents the lower or main section of the ladder, having side 35 pieces B and rungs C, and D is the upper slidable section, having side pieces E and rungs F. G and H are clamps secured to the side pieces B and E, respectively, which hold said sections together.

I is a plate secured to the inner surface of the lower or main section B, between two of the rungs thereof.

K is a hollow post projecting from the rear of the plate I and seated in a recess K' in the 45 section B, and L is a hollow post, and M a stop-pin, both projecting from the front of said plate.

N is a locking-lever mounted on the post L, provided at one end with a curved recess O and at the opposite end with a projection or toe P and a stop-shoulder Q.

R is a spring, one end secured to the side

piece of the ladder and the other end engaging the locking-lever and adapted to hold the lever in a position to be engaged by the rungs 55 of the slidable section of the ladder.

S is a screw-bolt which passes through the side piece of the ladder and the posts of the plate I for the purpose of securing the locking-lever in place.

T is a plate secured to the inner surface of the lower or main section B of the ladder, just below the plate I, and provided with a hollow post T', projecting from the rear thereof and seated in a recess T² in section B, and 65 a hollow post T³, projecting from the front thereof.

U is a tripping-dog mounted on post T³ and provided with a rounded under surface U' and a rounded head V and a notch V' at one 70 end and the opposite end weighted and provided with a beveled end, as at V².

V³ is a screw-bolt which passes through the side piece of the ladder and the posts of the plate T for the purpose of securing the tripping-dog in place.

W is a pulley secured to the inner face of the side of the lower section of the ladder, and X is a rope which is passed over the pulley W and both free ends of which are attached to the lower rung of the upper slidable section, making the rope a long loop, so that said section may be raised by hand.

It will be noticed that the upper slidable section is away from the person and the rope 85 at one side, so as to be out of the way.

The locking-lever is prevented from moving outward past the rungs of the slidable section by the stop-shoulder on the same abutting against the stop-pin on the plate I. 90 The rungs of the slidable section are spaced, so that when the two sections of the ladder are locked together the recess in the end of the locking-lever will be in engagement with a rung of said slidable section, and at the same 95 time the tripping-dog will rest on the next rung below, and when the slidable section is slid downward the rungs of the same will come in contact one at a time with the beveled end of the tripping-dog and cause said 100 dog to move the locking-lever outward a sufficient distance to allow the upper end of the lever to clear the said rungs.

I have described the locking-lever, trip-

ping-dog, &c., as applied to only one side of the lower or main section of the ladder; but they may be applied with equal facility to both sides. Instead of having two separate supporting-plates for the locking-lever and tripping-dog they may both be mounted on the same plate.

I do not wish to be limited to the precise construction as herein shown and described, 10 and the same may be varied somewhat without departing from the spirit of my invention.

The operation is as follows: The slideable section of the ladder being slid upward by 15 means of the rope or any other suitable means, the locking-lever and tripping-dog will pass the rungs of the same, and when it is desired to lock the ladder at a certain rung the locking-lever is stopped at a position just below 20 said rung, leaving the tripping-dog resting on the next rung below. Said slideable section is then slid slightly downward until the curved recess at the end of the locking-lever engages the rung. When it is desired to lower 25 the slideable section, it is raised, so that the end of the locking-lever is in a position about midway between the rung it has been engaged with and the next rung below, and the tripping-dog is below any rung of said section. 30 The said slideable section is then slid downward, and as each rung comes in contact with the beveled end of the tripping-dog it will slide down the same, move the said dog, and cause the head of the same to engage the projection of the locking-lever, which in turn 35 causes said lever to move outward against the action of the spring sufficiently to clear the rungs of the slideable section. It will be seen that when the slideable section is slid upward 40 the rungs thereof will retract the locking-lever against the action of the spring; but when said section is slid downward the tripping-dog will retract the locking-lever as each rung passes the dog.

45 Having thus described my invention, what I claim is—

1. An extension-ladder comprising a slideable section, a stationary section provided with a pivoted locking-lever having a recess 50 at one end adapted to engage the rungs of the slideable section, and a toe at the opposite end, a tripping-dog engaging said toe, the tripping-dog being operated by the slideable section and said locking-lever operated by the 55 tripping-dog, substantially as described.

2. An extension-ladder comprising a lower or main section provided with a stop-pin, a pivoted locking-lever having a recess at one end and a projection at the opposite end, a 60 shoulder to abut against the stop-pin, and a tripping-dog engaging said projection, an upper slideable section having rungs which engage the recess in the end of the locking-lever and lock the upper sliding section to the 65 lower section, and also engage the tripping-

dog to release said sliding section, substantially as described.

3. An extension-ladder comprising a stationary section provided with a pivoted locking-lever having a recess at one end, and a 70 projection at the opposite end, a spring bearing on said lever, a tripping-dog having a notch at one end with which said projection engages and the opposite end beveled, and a slideable section adapted to engage the beveled end of 75 the tripping-dog and the recess of the locking-lever, substantially as described.

4. An extension-ladder comprising a slideable section, a stationary section provided with a stop-pin, a spring-pressed pivoted locking-lever having a recess at one end to engage the rungs of the slideable section, a projection at the opposite end, and a stop-shoulder on the edge to abut against said stop-pin, 80 a spring, and a tripping-dog with a rounded 85 head at one end adapted to engage said projection, and its opposite end beveled and adapted to be engaged by the rungs of the slideable section, substantially as described.

5. An extension-ladder comprising an upper 90 slideable section, a lower section provided with a plate having a stop-pin, and hollow posts, one of said posts seated in a recess in the side of the section and the other post having a spring-pressed locking-lever thereon 95 provided with a shoulder to engage the stop-pin, and a tripping-dog for operating said locking-lever adapted to be operated by the rungs of the slideable section, substantially as 100 described.

6. An extension-ladder comprising an upper slideable section, a lower section provided with a spring-pressed locking-lever, and a weighted tripping-dog one end beveled and adapted to be engaged by the rungs of the 105 slideable section when the same is slid downward, the opposite end engaging the said locking-lever, the lower edge rounded and adapted to be engaged by the rungs of the slideable section when the same is slid upward, 110 substantially as described.

7. An extension-ladder comprising an upper slideable section, a lower section having plates with hollow posts extending from the front and rear thereof, the rear posts seated 115 in recesses in the side of the lower section, one of said plates provided with a spring-pressed lever pivoted on its front post and having a shoulder, a stop-pin, with which said shoulder engages, and a tripping-dog pivoted 120 on the front post of the other plate adapted to be operated by the rungs of the slideable section and move the locking-lever outward, substantially as described.

Signed by me, at Lebanon, New Hampshire, 125 this 30th day of March, 1901.

WALTER N. DERBY.
